UNITED STATES PATENT OFFICE.

JAMES J. HENNESSY, OF NEW YORK, N. Y.

LUBRICATOR.

Application filed September 10, 1925. Serial No. 55,603.

My invention relates to lubricators adapted to be used in connection with railway rolling stock and consisting in improvements upon the lubricators of the type illustrated in my prior Patent No. 1,412,741, and my copending application Serial No. 742,253, in which the pumping mechanism is operated by movement of the journal to and fro in the driving box.

10 One object of my present invention is to provide a lubricator of this type in which the lubricant pump may be easily removed from the cellar without disassembly of the cellar from the journal to which it is applied.

15 Another object of my invention is to provide a yielding support for the waste containing sub-cellars which will facilitate the insertion of the sub-cellars in the cellar when the latter is assembled with the driving box.

20 An additional object of my invention is to provide in a lubricant pump of the type used in my lubricator, means for preventing undesirable rotation of the pump parts and corresponding departure of the same from a desired position relative to the vertical.

A further object of my invention is to so construct a lubricator with lubricant reservoir that filling of the latter will not flood the lubricator.

30 Another object of my invention is to provide improved means for preventing the waste of lubricant by the centrifugal discharge of the same from the surface of the journal being lubricated.

35 Another object of my invention is to construct a lubricating cellar of the type referred to which may be applied to different driving boxes in which the cellar pin holes are located at different distances from the normal position of the journal to be lubricated, thereby avoiding a different cellar construction for every variety of driving box.

In the accompanying drawings which illustrate a selected embodiment of my invention—

45 Figure 1 is a vertical longitudinal section through my improved lubricator.

Figure 2 is a vertical transverse section taken substantially on line 2—2 of Figure 1.

50 Figure 3 is a fragmentary detail taken on line 3—3 of Figure 1.

Figure 4 is a fragmentary detail taken on line 4—4 of Figure 2.

55 The journal to be lubricated is indicated at A and it is to be understood that the same will carry an annular surface, such as the

wheel hub B, adapted to engage a contact rod 1 for operating the lubricant pump mechanism. The journal will support a box through the usual bearing C, the sides of the box being indicated in dot and dash lines at D in Figure 2.

The body of the lubricator includes a cellar 2 the inner end of which is united with a depending lubricant reservoir 3 having a filling 65 spout 4 and a removable cover 5 provided with an integral vertical portion 6 which also forms an inner end wall for the cellar 2. The top of the filling spout is substantially at the same level as the bottom of the cellar. Hence, when the reservoir is filled, the lubricant will not rise above the cellar floor.

70 A waste containing sub-cellars 7 is yielding supported from the floor of the cellar by a spring 8, the expansion movement of which is limited by a plate 9 pivoted at 10 on the cellar floor and free to be compressed by the sub-cellars to any necessary extent, but having its upward movement limited by the engagement of its pivoted end with the floor 75 of the cellar.

76 The bottom of the sub-cellars includes a cylindrical chamber 11 adapted to house the pump cylinder 12, the latter having fixed thereto a depending intake 13, which extends 80 into the lubricant reservoir 3 and is provided with a screen 14 and with a check valve 15. A hollow pump piston or plunger 16 is slidably mounted in cylinder 12 and includes a flap valve 17 pivoted at its upper edge and 85 also carries a projecting stem 18 extending lengthwise of the sub-cellars into a position where it may engage the inner end of contact rod 1. When the plunger is forced inwardly by contact rod 1 it is subsequently returned to its original position by a spring 29 which is seated on a shoulder formed on the end of the plunger. To permit oil to pass 90 through the end of the plunger, the same is perforated beyond the spring seat as indicated at 30. Transverse passages 31 in the plunger lead from perforations 30 to the axial opening in the plunger leading from flap valve 17.

95 In order to prevent rotation of plunger 16 in its cylinder 12, I provide the plunger with an upwardly extending dowel 19 adapted to slide in a longitudinal slot provided in the upper portion of cylinder 12. This prevents the rotation of the plunger such as will interfere with the easy operation of the flap valve 17.

100 In order to prevent rotation of plunger 16 in its cylinder 12, I provide the plunger with an upwardly extending dowel 19 adapted to slide in a longitudinal slot provided in the upper portion of cylinder 12. This prevents the rotation of the plunger such as will interfere with the easy operation of the flap valve 17.

The outer end of cylinder 12 is adapted to contact with the inner face of wall 6 provided on removable cover 5 and upon removal of cover 5 from the lubricator, cylinder 12 with plunger 16 may be easily withdrawn from the remainder of the lubricator and repaired or replaced, if necessary.

To prevent the discharge of lubricant by the journal over the sides of the cellar, I provide sheet metal shields 20 extending upwardly from the inside of the cellar side walls 21 into engagement with the lower edges of the journal bearing C. Shields 20 are preferably yieldingly supported by springs 22 mounted on a sheet metal base 23, thereby providing an adjustable shield for the purpose described.

In the earlier manufacture of my lubricator, it has been customary to provide the cellar with an integral lug for receiving the cellar pin. This made necessary the special drilling and, in many cases, the special location of the lug in order to accommodate driving boxes having their cellar pin holes located at different heights. In order to eliminate this undesirable feature, I have provided the depending wall 24 of the reservoir with integral ears 25 located a substantial distance below the bottom of the cellar and below any likely location of the cellar pins. For each installation, I provide small bars 26 which may be bolted to ears 25 and extend upwardly therefrom as far as necessary to take the cellar pins E and to support the bottom of the cellars. This construction permits me to make the depressed middle portion 27 of the cellar wider than could be done otherwise, and it is comparatively easy to provide various dimensioned bars for applying the cellar to different types of driving boxes.

The cellar may be provided with downwardly facing shoulders 28 adapted to rest on corresponding driving box shoulders or, where the driving boxes are provided with a straight inner face, the cellar of said wall may extend downwardly without shoulder 28.

I claim:

1. In a journal lubricator, a lubricant distributing chamber adapted to underlie the journal to be lubricated, a lubricant reservoir extending substantially below the level of the bottom of said chamber, a pump positioned in said chamber and including an intake member extending downwardly into said reservoir, and a removable wall on the upper portion of said reservoir whereby said pump may be removed from the lubricator while the same is applied to a journal.

2. In a journal lubricator, a lubricant distributing chamber adapted to underlie the journal to be lubricated, a lubricant reservoir extending substantially to one side of and below the level of the bottom of said chamber, a pump positioned in said chamber and

including an intake member extending outwardly therefrom and downwardly into said reservoir, and a removable wall on said reservoir above the level of the bottom of said chamber whereby said pump and its intake member may be removed from the lubricator while the same is applied to a journal.

3. In a journal lubricator, a cellar, a sub-cellular having a hollow bottom wall opening at one end, horizontally movable lubricant-pump elements positioned in the lower wall of said sub-cellular and removable therefrom through said opening, and a detachable wall on said cellar abutting one of said pump elements to maintain their assembly with said sub-cellular.

4. In a journal lubricator, a cellar, a pump including a reciprocating contact rod for contact with a journal wheel or like annular surface, a plunger operated by said rod and a cylinder for said plunger positioning the latter adjacent to said rod, and a removable end wall on said cellar for retaining said cylinder in place against the thrust of said rod and plunger.

5. In a journal lubricator, a cellar, a sub-cellular therein, a pump carried by said sub-cellular and including a reciprocating contact rod for engagement with a journal wheel or like annular surface, a plunger operated by said rod and a cylinder for said plunger positioning the latter adjacent to said rod, and a removable end wall on said cellar for retaining said cylinder in place in said sub-cellular against the thrust of said rod and plunger.

6. In a journal lubricator, a cellar comprising a body portion for extending under the journal to be lubricated and a depending reservoir at one end thereof, means comprising a removable cover for said reservoir and a removable end wall for said body, a pump extending substantially throughout the length of said body and including an intake extending substantially to the bottom of said reservoir, said pump and intake being removable from said cellar in the absence of said means.

7. In a journal lubricator, a cellar comprising a body portion for extending under the journal to be lubricated and a depending reservoir at one end thereof, means comprising a removable cover for said reservoir, a removable end wall for said body, a sub-cellular carrier by said cellar, and a pump mounted in said sub-cellular and extending substantially throughout the length of said body and including an intake extending substantially to the bottom of said reservoir, said pump and intake being removable from said cellar in the absence of said means.

8. A lubricant cellar enclosure adapted to be seated in a lubricator and including adjustable members adapted to extend upwardly to contact with the lower face of a

journal bearing to prevent centrifugal discharge of lubricant by the journal.

9. In a journal lubricator, a cellar having a lubricant reservoir, a sub-cellар having a substantially enclosed chamber, and detachable pump elements removably mounted in said chamber and having an integral extension projecting into said reservoir.

10. In a journal lubricator, a cellar, a sub-cellar including a cylindrical chamber, a cylindrical pump mechanism fitting in said chamber enclosing the end thereof, and a removable wall on said cellar abutting an end of said mechanism to prevent removal thereof from said chamber, and a pump operating element extending into said chamber from the end thereof opposite said wall.

11. In a journal lubricator, a cellar, a spring carried thereby, a sub-cellar yieldingly supported by said spring, and a plate pivoted on said cellar and extending over said spring and elements limiting movement of said plate by said spring to facilitate insertion of the cellar between said spring and a journal to be lubricated.

12. In a journal lubricator, a cellar, a spring carried thereby, a sub-cellar yieldingly supported by said spring, and a plate pivoted on said cellar and provided with a rearwardly projecting lip for engaging said cellar to limit pivotal movement of said plate, said plate extending over said spring and holding it compressed to facilitate insertion of the sub-cellar between said spring and a journal to be lubricated.

13. In a journal lubricator, a sub-cellar, a pump carried thereby and including a cylinder, and a reciprocating plunger therein provided with a flap valve pivoted at an upper portion of its edge to the plunger body, and means for preventing rotation of said plunger in said cylinder.

14. In a journal lubricator, a sub-cellar, a pump carried thereby and including a cylinder having a longitudinal slot, a reciprocating plunger therein provided with a flap valve pivoted at an upper point on its edge to the plunger body, and a stud in the side of said plunger projecting into said slot.

15. In a journal lubricator, a sub-cellar, a

pump carried thereby including a cylinder, a hollow plunger having an annular shoulder and an extension therefrom of reduced diameter to cooperate with the operating element, a plunger return spring surrounding said extension and seated in said shoulder, said shoulder being perforated outside of the spring seat forming portion to permit passage of lubricant therethrough.

16. In a journal lubricator, a member containing means for supplying lubricant to a journal, and an enclosure for said member adapted to contact with the journal bearing and having adjustable walls to accommodate variations in the relative positions of said member and bearing.

17. A lubricant cellar enclosure adapted to be seated in a lubricator and including adjustable side walls adapted to extend upwardly to contact with the lower surface of a journal bearing to prevent centrifugal discharge of lubricant by the journal.

18. In a journal lubricator, a cellar, a lubricant reservoir extending downwardly from one end of said cellar, ears on the side of said reservoir and spaced from said cellar, and removable bars adapted to be attached to said ears and to a driving box or pedestal.

19. In a journal lubricator, a cellar, the central portion of the bottom of which is depressed below the side portions of the bottom, a depending wall at one end of said cellar, lugs on said wall extending under said cellar and spaced therefrom, and separate bars for attachment to said lugs and adapted to extend upwardly therefrom into an area abreast of the depressed cellar portion.

20. In a journal lubricator, a cellar having a downwardly facing shoulder, the lower wall of said cellar having a laterally extending recess below said shoulder adapted to receive a bolt head, a wall depending below said shoulder and recess, an ear on said wall, and a bar secured to said ear and extending upwardly past said recess to engage said shoulder.

In testimony whereof I hereunto affix my signature this 4th day of September, 1925.

JAMES J. HENNESSY.
